Primary Examiner—Cathron C. Brooks*Assistant Examiner*—Austin Murphy(74) Attorney, Agent, or Firm—Lathrop & Gage, L.C.(57) CLAIM

The ornamental design for the medical information binder, as shown and described.

DESCRIPTION

FIG. 1 is a front perspective view of the interior of the medical information binder in an partially open position;

FIG. 2 is a front view thereof;

FIG. 3 is a back view thereof;

FIG. 4 is a top end view thereof;

FIG. 5 is a bottom end view thereof;

FIG. 6 is a first side view thereof; and,

FIG. 7 is second side view thereof.
